UNITED STATES PATENT OFFICE.

JAMES H. RAND, OF NORTH TONAWANDA, NEW YORK.

INDEX DEVICE.

1,302,850.

Specification of Letters Patent.

Patented May 6, 1919.

Application filed May 17, 1918. Serial No. 235,110.

To all whom it may concern:

Be it known that I, JAMES H. RAND, a citizen of the United States of America, and resident of North Tonawanda, in the county 5 of Niagara and State of New York, have invented new and useful Improvements in Index Devices, of which the following is a specification.

This invention relates to visible indexes 10 of the kind comprising a frame supporting a series of cards or index elements held in overlapped spaced relation with their margins exposed to view for displaying names or other index characters.

15 In the accompanying drawings which illustrate the invention,—

Figure 1 is a horizontal cross section of a preferred form of the frame;

20 Fig. 2 is a face view of the frame partly broken away;

Fig. 3 is a face view of one of the cards or index elements;

25 Fig. 4 is a longitudinal section of part of the frame on line 4—4 of Fig. 2, showing a number of nested or interlocked index elements therein; and

Fig. 5 is a horizontal cross section of a detail showing a modification of the frame.

30 In order to secure an index of the largest possible capacity it has heretofore been the practice to provide a double faced frame or panel, that is, to provide both the obverse and reverse sides of the frame with the several structural features adapting the frame 35 to receive and hold the index elements. This has usually been accomplished by making two similar single faced frame members, each having a sheet metal back and its own marginal flanges for engaging the index ele- 40 ments, and fastening the two members together back to back to form a double faced structure. The resulting frame has a double or two ply body, is necessarily too thick and bulky for the greatest economy of space

45 where a large number of frames are used in the same equipment, and demands too great weight and cost of material. The principal objects of the present invention are to provide a structure which shall be 50 lighter, thinner and more compact than heretofore, while possessing the functional characteristics of double frames heretofore proposed, and which shall make it possible to use a single ply body of sheet material, 55 provided on both sides with recessed channels for the supporting and spacing tabs of

the index elements, at the same time securing the thinnest possible structure from face to face when the index elements are in place.

The index frame comprises a single ply 60 body A of sheet metal, or other suitable sheet material, having longitudinal marginal flanges on both faces of the body to engage lateral projections on the index elements and hold the index elements in the 65 frame.

The body A is bent to form a pair of shallow, lengthwise extending channels on each face of the frame, depressed below the plane P of the body A, the pair of channels on the obverse side of the frame being indicated at B, B, and the pair of channels on the reverse side being indicated at C, C. The channels of each pair are disposed at 70 opposite sides of the central longitudinal axis X—X of the frame, and the two pairs B, B and C, C, on opposite faces of the frame are laterally offset with relation to said central axis, to a similar extent but in opposite directions. Thus, when facing 75 either side of the frame the lateral offset of the pair of channels B, B, or C, C, as the case may be, is in the same direction, namely, to the left of the central axis, as shown in the drawings, thus producing two identical 80 faces adapted to receive identical cards or index elements.

In the preferred form the marginal flanges D are formed of separate strips of 85 sheet metal secured to the body of the frame by riveting, welding, or soldering. These provide the usual grooves or guide channels for receiving the ends of lateral projections on the index elements to hold the latter in the frame. The flanges D may be of any 90 usual or preferred cross section, that herein shown being the subject of a separate application Ser. No. 229,031, filed April 17, 1918.

95 The cards or index elements, which may be of cardboard, sheet celluloid, or other suitable sheet material, comprise each a body E, having lateral projections F, F, adjacent to one margin to engage the flanges D, D, at the sides of the frame. The body E may also be provided, if desired, with projections G, G, adjacent to the opposite or free margin, to rest on the outer faces of the flanges. Each index element also has a pair 100 of supporting and spacing tabs, H, H, preferably cut from the body of the element and bent slightly to project from the body, to engage the edge of the next adjacent element 105 110

and support the elements in overlapped spaced relation. The tabs H, H, of each element are disposed at opposite sides of the central vertical axis Y, Y, of the element, 5 and the pair of tabs is laterally offset with relation to said central axis in the same direction and to substantially the same extent as the corresponding channels of the frame. Thus the projecting tabs H, H, will register 10 with, and extend into the channels B, B, or C, C, according as the elements are applied to one side or the other of the frame. The channels prevent the tabs from bearing with undue pressure against the back or body of 15 the frame, thereby reducing friction or binding and affording freedom of motion when the elements are slid lengthwise of the frame, and at the same time under certain conditions aiding to guide the elements and 20 keep them from twisting or cramping as they slide in the frame. Entries may be placed directly on the cards E, or, if it is desired to keep them merely as holders for other cards or sheets, they may be equipped 25 with any usual or preferred means for holding a detachable insert card or sheet on which the entries may be written.

By offsetting the channels laterally in opposite directions on opposite faces of the 30 frame, and similarly offsetting the tabs H, H, the thickness of the structure from face to face is reduced to a minimum, a single ply body A may be used and cards or index 35 elements of identical form may be used at pleasure on both faces of the frame.

Instead of making both flanges D of separate strips of material, one flange, D', may be bent up from the body A of the frame and the other made of a separate piece of material and fastened to the body, as shown in 40 Fig. 5.

Reference is made to my copending application Serial No. 195,700, filed October 10, 1917, wherein channels in the back of 45 the frame for receiving the supporting and spacing tabs of the index elements are claimed more generically.

I claim:

1. An index frame comprising a body of 50 sheet material having a pair of lengthwise extending channels on each face of the frame, the channels of each pair being disposed at opposite sides of the central longitudinal axis of the frame, and the pairs on 55 the opposite faces of the frame being laterally and similarly offset in opposite directions with relation to said central axis.

2. An index frame comprising a body of 60 sheet material having a pair of lengthwise extending channels on each face of the frame, the channels of each pair being disposed at opposite sides of the central longitudinal axis of the frame, and the pairs on 65 the opposite faces of the frame being laterally and similarly offset in opposite direc-

tions with relation to said central axis, and longitudinal marginal flanges on both faces of the body.

3. An index frame comprising a body of sheet material having a pair of lengthwise 70 extending channels on each face of the frame, the channels of each pair being disposed at opposite sides of the central longitudinal axis of the frame, the pairs on the opposite faces of the frame being laterally 75 and similarly offset in opposite directions with relation to said central axis, and longitudinal marginal flanges on both faces of the body, one at least of which at each margin of the frame is formed of a separate 80 strip of sheet material secured to the body.

4. An index frame comprising a body of sheet material having a pair of lengthwise extending channels on each face of the frame, the channels of each pair being disposed at opposite sides of the central longitudinal axis of the frame, the pairs on the opposite faces of the frame being laterally and similarly offset in opposite directions 85 with relation to said central axis, and longitudinal marginal flanges on both faces of the body formed of separate strips of sheet material secured to the body.

5. An index frame comprising a single 90 ply body of sheet material bent to form a 95 pair of lengthwise extending channels on each face of the frame, the channels of each pair being disposed at opposite sides of the central longitudinal axis of the frame, and the pairs on the opposite faces of the frame being laterally and similarly offset in opposite directions 100 with relation to said central axis.

6. An index comprising a frame having a body of sheet material provided with a pair 105 of lengthwise extending channels on each face of the frame, the channels of each pair being disposed at opposite sides of the central longitudinal axis of the frame, and the pairs on the opposite sides of the frame being laterally and similarly offset in opposite 110 directions with relation to said central axis, and a series of index elements each having a pair of supporting and spacing tabs projecting from the body of the element to engage and support the next adjacent element 115 in overlapped spaced relation, each pair of said tabs being laterally offset with relation to the central vertical axis of the element to correspond with the offsets of the channels, whereby said index elements may be applied to either side of the frame with their tabs 120 registering with the channels.

7. An index comprising a frame having a single ply body of sheet material bent to 125 form a pair of lengthwise extending channels on each face of the frame, the channels of each pair being disposed at opposite sides of the central longitudinal axis of the frame, and the pairs on the opposite sides of the 130

frame being laterally and similarly offset in opposite directions with relation to said central axis, and a series of index elements each having a pair of supporting and spacing tabs projecting from the body of the element to engage and support the next adjacent element in overlapped spaced relation, each pair of said tabs being laterally offset with relation to the central vertical axis of the element to correspond with the offsets of the channels, whereby said index elements may be applied to either side of the

frame with their tabs registering with the channels.

8. An index element of sheet material having a pair of supporting and spacing tabs projecting from the body of the element, said tabs being disposed at opposite sides of the central vertical axis of the element, and the pair of tabs being laterally offset with relation to said central axis. 15
